(57) **CLAIM**

The ornamental design for flexible orthosis, as shown and described.

DESCRIPTION

FIG. 1 is a Top View of the flexible orthosis;

FIG. 2 is a Bottom View of the flexible orthosis;

FIG. 3 is a Top Reference View showing the flexible orthosis in use;

FIG. 4 is a Bottom Reference View showing the flexible orthosis in use;

FIG. 5 is a Right Side Reference View showing the flexible orthosis in use; and,

FIG. 6 is a Left Side Reference View showing the flexible orthosis in use.

The features presented in dashed lines correspond to environment and do not form part of the claimed design.

1 Claim, 6 Drawing Sheets

FIG. 1

FIG. 2

FIG. 3

FIG. 4

FIG. 5

FIG. 6
